INDUCTION ROTOR

Robert G. Le Tourneau, Longview, Tex., assignor
to R. G. Le Tourneau, Inc., Stockton, Calif., a
corporation

Application October 27, 1947, Serial No. 782,380

10 Claims. (Cl. 172—120)

1

This invention is directed to, and it is an object to provide a novel rotor for an A. C. induction motor of high torque type; the feature of such rotor being the design thereof for the effective and accelerated dissipation of the heat from the current induced in the conductor bars.

Another object of the present invention is to provide an induction rotor, as above, wherein the heat dissipating means includes a novel resistance end bell on one end of the rotor in electrical connection with the conductor bars; such end bell being of stainless steel and thus capable of withstanding high heat, without damage or scaling, when the motor is operated much below synchronous speed.

An additional object of the invention is to provide an induction rotor which can be run safely at high speed; the parts being formed and assembled in a manner to prevent impairment by centrifugal force.

A further object of the invention is to produce a practical and rugged induction rotor and one which will be exceedingly effective for the purpose for which it is designed.

These objects are accomplished by means of such structure and relative arrangement of parts as will fully appear by a perusal of the following specification and claims.

In the drawings:

Figure 1 is a sectional elevation of the induction rotor.

Figure 2 is an enlarged fragmentary elevation of said induction rotor.

Figure 3 is a perspective view of one of the conductor bar units, detached.

Referring now more particularly to the characters of reference on the drawings, the induction rotor is formed on the motor shaft 1 of an A. C. induction motor of high torque type. The shaft 1 is reduced in diameter in part to form a radical shoulder 2 thereon and a laminated rotor 3 is engaged on the shaft in abutting relation at one end against such radial shoulder. The rotor 3 is maintained against relative rotation on the shaft 1 by means of a longitudinal key 4.

Beyond the end of the laminated rotor 3, opposite the radial shoulder 2, the shaft supports a resistance end bell 5 of stainless steel disposed concentric to said shaft. The bell includes an elongated hub 6 and an inner end wall 7.

The hub 6 is retained against relative rotation on the shaft 1 by an extended end portion of the key 4; the inner end wall 7 of the resistance end bell bearing directly against the adjacent end of the laminated rotor 3.

Longitudinal displacement of the rotor 3 and hub 6 in a direction away from the radial shoulder 2 is prevented by a retainer sleeve 8 on the shaft between the outer end of the hub 6 and a bear-

2

ing unit 9 likewise mounted on the said shaft and maintained against axial displacement in the motor frame by means not here shown.

The resistance end bell 5 flares outwardly in a direction away from the laminated rotor 3 until, at its free end, said bell is of greater diameter than the rotor 3. At said free end the resistance end bell 5 is formed with an annular stiffening flange 10 of substantial width which projects radially outward. This flange acts to eliminate distortion of the bell 5 which might otherwise occur when the rotor is running at high speed, or when the resistance end bell 5 is operated at high heat.

Between the inner end wall 7 and the annular stiffening flange 10 the resistance end bell 5 is formed with a plurality of circumferentially spaced slots 11 cut therethrough and extending in a direction radiating from the apex of said bell. The slots 11 are of substantial width and are rounded at the ends, as at 12.

A plurality of heavy duty conductor bars 13 of copper or similar high conductivity metal are fitted in circumferentially spaced slots 14 in the laminated rotor 3 adjacent its periphery; the slots running parallel to the shaft axis. The conductor bars 13 are in pairs and each pair projects longitudinally from the laminated rotor 3 toward and through one of the slots 11. At the end, adjacent the rounded outer end 12 of the corresponding slot 11, each pair of conductor bars 13 is closed, in electrical relation, by a U-shaped end 15. Each pair of conductor bars 13, with its U-shaped end portion 15, may be termed a conductor bar unit, indicated at 16, and one of which is shown detached in Fig. 3.

The U-shaped end portions 15 of the conductor bar units 16 are bent laterally outward to an incline matching the taper or flare of the resistance end bell 5, and said end portions 15 thus engage the bell 5 in substantially symmetrical or matching relation to the rounded outer ends 12 of the slots 11. The U-shaped end portions 15 of the conductor bar units 16 are permanently affixed to the end bell 5 at the outer end portions 12 of the slots 11 by brazing or the like, as shown at 17.

At the end of the laminated rotor 3, opposite the end bell 5, the conductor bars 13 project outwardly slightly and are thence bent laterally, as at 18, into engagement with said end of the rotor. This further locks up the assembly against axial separation.

When the above described induction rotor is in use the current induced in the conductor bars 13 feeds to the resistance end bell 5 causing heating of the latter and from which end bell the heat dissipates rapidly and effectively. This dissipation of the heat is improved by reason of the fact that the end bell 5 is of stainless steel, which also

permits said end ball to run at high heat without distortion or scaling. The character of stainless steel is such that it is not damaged by high heat nor does it give off undesirable scaling at such heat, which would otherwise impair proper operation of the motor by deposit of damaging scale therein.

Further, the resistance end bell 5 is stamped from a single piece of metal and this fact, together with the inclusion of the annular stiffening flange 10 further minimizes distortion or damage due to high heat or high speed rotation.

As the conductor bars 13 are exposed outwardly and inwardly of the end bell 5, a fan effect is accomplished circulating air through the slots 11 and about the end bell 5, upon operation of the motor, to assist in the dissipation of the heat. Air circulation through the rotor unit, is further enhanced by circumferentially spaced cooling bores 19 which extend through the rotor and inner end wall 7, as shown.

From the foregoing description it will be readily seen that there has been produced such an induction rotor as substantially fulfills the objects of the invention as set forth herein.

While this specification sets forth in detail the present and preferred construction of the induction rotor, still in practice such deviations from such detail may be resorted to as do not form a departure from the spirit of the invention, as defined by the appended claims.

Having thus described the invention, the following is claimed as new and useful and upon which Letters Patent is desired:

1. An induction rotor unit comprising a rotor including circumferentially spaced conductor bars extending lengthwise to and beyond one end of the rotor, a resistance end bell supported adjacent said one end of the rotor concentric to the rotor axis, the extended conductor bars being electrically connected to said resistance end bell, and means mounting the rotor and end bell for rotation in unitary relation; said means including a hub on the end bell engaging said one end of the rotor, a shaft on which the rotor and hub are secured against relative rotation, an abutment on the shaft engaged by the opposite end of the rotor, an axially fixed bearing unit on the shaft beyond the hub, and a sleeve on the shaft engaged between the hub and bearing unit.

2. An induction rotor unit comprising a rotor including circumferentially spaced conductor bars extending lengthwise to and beyond one end of the rotor, a resistance end bell supported adjacent said one end of the rotor concentric to the rotor axis, the extended conductor bars being electrically connected to said resistance end bell, and means mounting the rotor and end bell for rotation in unitary relation; the end bell flaring outwardly in a direction opposite the rotor and having a plurality of circumferentially spaced slots therein, the conductor bars being arranged in pairs corresponding to and projecting through the slots, each pair including a continuous outer end portion electrically connected to the end bell.

3. An induction rotor unit comprising a rotor including circumferentially spaced conductor bars extending lengthwise to and beyond one end of the rotor, a resistance end bell supported adjacent said one end of the rotor concentric to the rotor axis, the extended conductor bars being electrically connected to said resistance end bell, and means mounting the rotor and end bell for rotation in unitary relation; the end bell flaring outwardly in a direction opposite the rotor and

having a plurality of circumferentially spaced slots therein, the conductor bars being arranged in pairs corresponding to and projecting through the slots, each pair including a continuous outer end portion electrically connected to the end bell, the slots radiating from the apex of the end bell and being elongated.

4. A rotor unit as in claim 2 in which the continuous end portion of each pair of conductor bars is generally U-shaped, and inclined in generally matching relation to the flare of the end bell.

5. An induction rotor unit comprising a rotor including circumferentially spaced conductor bars extending lengthwise to and beyond one end of the rotor, a resistance end bell supported adjacent said one end of the rotor concentric to the rotor axis, the end bell being of lesser diameter at its inner end than the diameter of the adjacent end of the rotor and thence flaring outwardly in a direction opposite said rotor, there being circumferentially spaced slots in the end bell, the extended conductor bars being disposed in pairs corresponding to and projecting through the slots, said pairs having continuous outer end portions connected to the end bell, and means mounting the rotor and end bell for rotation in unitary relation.

6. An induction rotor unit comprising a rotor including circumferentially spaced conductor bars extending lengthwise to and beyond one end of the rotor, a resistance end bell supported adjacent said one end of the rotor concentric to the rotor axis, the end bell being of lesser diameter at its inner end than the diameter of the adjacent end of the rotor and thence flaring outwardly in a direction opposite said rotor, there being circumferentially spaced slots in the end bell, the extended conductor bars being disposed in pairs corresponding to and projecting through the slots, said pairs having continuous outer end portions connected to the end bell, and means mounting the rotor and end bell for rotation in unitary relation; the end bell having an annular, radially outwardly projecting flange on its free end.

7. An induction rotor unit comprising a rotor which includes circumferentially spaced conductor bars, an end bell, such end bell having a relatively flat base disposed adjacent one end of the rotor and mounted for rotation with the rotor, the body of the bell flaring outwardly from the base, said conductor bars projecting a distance beyond the end of the rotor adjacent which the bell is disposed, the outer ends of the bars being attached to the bell.

8. An inductor rotor unit comprising a rotor which includes circumferentially spaced conductor bars, an end bell, such end bell having a relatively flat base disposed adjacent one end of the rotor and mounted for rotation with the rotor, the body of the bell flaring outwardly from the base, said conductor bars projecting a distance beyond the end of the rotor adjacent which the bell is disposed, the projecting ends of the bars extending through the flaring body of the bell, and the outer ends of the bars being attached to the body of the bell.

9. An induction rotor unit comprising a rotor including circumferentially spaced conductor bars extending lengthwise to points beyond one end of said rotor, and an end bell of high resistance, the closed end of the bell lying adjacent the rotor and the wall of the bell flaring outwardly in a direction away from the rotor, the outer ends of the bars being connected with the

walls of said end bell at a point intermediate the ends of such end bell.

10. A rotor unit as in claim 9 in which the end bell consists of stainless steel.
